UNITED STATES PATENT OFFICE.

VIRGIL T. LEAK AND IRVING J. THOMAS, OF COCOANUT GROVE, FLORIDA.

HEAD-COVERING FOR PROTECTION AGAINST INSECTS.

1,359,393.

Specification of Letters Patent. Patented Nov. 16, 1920.

Application filed November 18, 1919. Serial No. 338,919.

To all whom it may concern:

Be it known that we, VIRGIL T. LEAK and IRVING J. THOMAS, citizens of the United States, and residents of Cocoanut Grove, in the county of Dade, State of Florida, have invented certain new and useful Improvements in Head-Coverings for Protection Against Insects, of which the following is a specification.

10 The present invention relates to a head covering or screen for protection against insects, such as flies, mosquitos, bees, and the like.

15 The primary object of the invention is to improve the construction of this general class of devices, whereby not only is the device capable of being worn with utmost comfort, but its construction is such as to permit the wearer to perform many kinds 20 of laborious tasks which were impossible with heretofore known like devices.

Another object is to so construct the device that it may be used with various hat models and readily exchanged from one to 25 the other.

Other objects will appear upon reference to the accompanying drawing, in which—

Figure 1 is a perspective view of the device attached to a hat;

30 Fig. 2 is a side view; and

Fig. 3 is a cross-section of a hat brim, showing the manner of attaching the device.

Referring to the drawing in detail, A represents a conventional type of hat, having the usual brim, to which is attached the device, which, in its preferred form, comprises a screen 5, composed of any substantially flexible material, such as ordinary small-mesh screen wire. The screen is preferably 40 of a single piece, formed to provide a veil-shaped covering, with its ends joined together, and having a marginal portion bent to provide an attaching flange 6 for securing the device to the hat brim. In order to 45 adapt the flange 6 to the shape of the brim, it is cut, as at 7, at different points, so that the confronting edges may be overlapped. Suitable fasteners 8 are employed to impale the hat brim (see Fig. 3), with the flange 50 confined between their heads and the hat brim. This form of attachment enables the device to be applied to and removed from the hat at will.

Attention is called to the peculiar cut of the screen, as, for instance, the curved sides 9, terminating in an elongated front extension 10, which enables the wearer to observe objects around his feet or close up. Attached to the lower end of the screen is the apron 11, consisting of some light cloth material, cut in a manner to permit it to fall loosely upon the wearer's shoulders, close to the neck, thus closing the bottom of the screen. The apron 11 is fastened with a safety pin to the wearer's clothing at point 65 12, directly beneath the elongated extension 10. The apron will not in any way interfere with the free use of the wearer's arms or obstruct his vision in a downward direction, in view of the extension 10. As above 70 stated, the lower edge 9 of the screen is curved, the curvature increasing from the back to the front of the device, thus providing the elongated extension heretofore mentioned. Although the curved lower edge of 75 the screen terminates above and does not contact with the shoulders of the wearer, its curvature, nevertheless, conforms to the general contour of a person's shoulders. This helps to permit the device being worn with 80 comfort and freedom of movement of the body.

Claim.

A device of the character described comprising a screen having its upper marginal portion flanged inwardly to afford a hat brim engaging edge, said flanced marginal portion being cut transversely at intervals and the confronting edges thereof overlapped, said screen also having a curved lower edge, 85 the curvature of the said lower edge increasing in a downward direction from the back to the front of the device and providing an elongated extension on the device, a bottom closure for the screen comprising an apron 90 secured to the said lower edge and adapted to terminate around the shoulders of the wearer of the device, and means for detachably securing the flanced marginal portion to the hat brim at the points where the confronting edges of the transverse cuts of the flanged marginal portion overlap.

VIRGIL T. LEAK.
IRVING J. THOMAS.
